Joseph H. Cone, Bridgeport, Conn., assignor to Casco Products Corporation, Bridgeport, Conn., a corporation of Connecticut

Application April 18, 1951, Serial No. 221,650

5 Claims. (Cl. 38—77)

This invention relates to steam flatirons of the type having a tank or boiler, and in its more specific aspect more particularly to such irons having a hinged handle structure extending over the tank, provided with stopper means to close a funnel-like filling opening in the tank.

This invention is a modification of the invention disclosed in my copending application, Serial No. 128,270, filed November 19, 1949.

In some irons of this type the filler opening or orifice is located at the bottom of a funnel which has a relatively wide mouth secured to the top wall of the tank, the funnel extending down into the tank. By such construction the filling of the tank is obviously made very easy, and the likelihood of spillage during the filling operation is minimized.

It is an object of the present invention to provide an improved steam iron construction, particularly with regard to the closure for the filling opening and to the latch means for the handle which makes allowances for the tolerances and variations present in mass production. This is accomplished, for example, where the iron is constituted of separate sheet metal boiler and casing parts having superposed top walls possessing a certain degree of yieldability, the stopper mounting and latch therefor is mounted on the casing wall whereas the seal or funnel of the filler opening, which is engaged by the stopper, is mounted on the boiler wall. The yield of the rubber-like sealing member and of the casing and boiler walls enable the latch parts and stopper and filler opening to be positioned less critically and still maintain a constant force between the stopper and the seat therefore in said opening.

Or, where the latch has spring means associated with it to prevent looseness, I rearrange the spring means to provide the latch with a limited amount of yield under pressure whereby in conjunction with a yieldable rubber-like stopper element it can function to accommodate a rigid simplified stopper mounting.

In another embodiment of the invention I incorporate a certain degree of yield in the funnel or seat itself, to allow for variations and tolerances in manufacture, and have found that this results in a desirable simplification and economy of the parts since the funnel yieldability can be provided in an extremely simple manner.

By utilizing the yieldability of various components of the iron as set forth above, the stopper member for the filler opening may comprise a simple sealing annulus or disk mounted on a rigid stud secured to the underside of the handle structure. The sealing disk may be loosely carried by the end of the stud as illustrated in one embodiment of the invention, or it may be rigidly carried by the stud and adjustably positioned on the handle structure by the use of shims or spacer washers on the stud.

Still another object of the invention is to provide an improved steam iron as above, which has relatively few parts of simple structure, and which is economical to fabricate and reliable in use.

2

Other features and advantages will hereinafter appear. In the accompanying drawings:

Figure 1 is a side view partly in elevation and partly in vertical section, of an improved steam iron made in accordance with the invention.

Fig. 2 is a view somewhat similar to Fig. 1, but showing the handle of the iron in raised position to enable the boiler to be filled.

Fig. 3 is a fragmentary view partly in elevation and partly in section, showing a rear corner of the iron and the hinge and latch mechanism thereof.

Fig. 4 is a fragmentary side elevational view of the rear of the iron and casing, showing the hinge and locking aperture for the pintle or hinge pin.

Fig. 5 is a perspective view of the pintle or hinge pin.

Fig. 6 is a top or plan view of the stopper assembly.

Fig. 7 is a diametric section taken on line 7—7 of Fig. 6.

Fig. 8 is a vertical section through a novel latching mechanism of the iron, the latch being in locking position.

Fig. 9 is a view like Fig. 8, but with the latch in released position.

Fig. 10 is a fragmentary vertical sectional view of the filler opening and funnel of the steam iron, showing a novel funnel mounting.

Fig. 11 is a detail in vertical section, showing a stopper and mounting therefor illustrating a modification of the invention.

The steam iron embodying the present invention as shown in Figs. 1 and 2 comprises a sole plate 20 having an electric heating element 21 controlled by the usual thermostat (not shown) having an adjusting shaft 22 and thermostat knob 23. The sole plate 20 has disposed on it a casing 24 in which a boiler 25 is mounted, said boiler being secured by means of a threaded sleeve 26 and steam tube 27 to a cover plate 28 of a steam chamber 29 located in the forward portion of the sole plate 20. The cover plate 28 is fastened to the sole plate 20 by screws 30 as shown.

Steam is brought into the chamber 29 through the steam tube 27 which extends into a tapered steam dome 31 mounted on the top walls of the boiler 25 and casing 24. Baffles 32, 33 and 34 are provided around the tube 27 to prevent water in the boiler 25 from splashing into the tube and passing downward into the steam chamber 29.

For the purpose of filling the boiler 25 a filler opening 35 is provided in the top walls of the boiler and casing. Secured to the edge portions of the filler opening is a funnel 36 having at its bottom an angularly and rearwardly extended deflector 37. The funnel 36 is of relatively large diameter to enable the boiler 25 to be easily and conveniently filled without spillage. However, because the funnel 36 extends downward into the boiler 25 it prevents the boiler when inverted from completely emptying itself of water.

In accordance with the present invention novel means are provided on the boiler 25, providing an unobstructed discharge passage from the lowermost point of the boiler when the iron is inverted into emptying position, whereby substantially all the water in the boiler may run out. This means, in the embodiment of the invention illustrated herein, includes the steam dome 31 and a discharge opening 38 in the top of the steam dome. In addition, it includes the top wall of the boiler 25 which is so shaped that no obstructions are presented to the flow of water to the steam dome when the iron is inverted for emptying. Accordingly, by the present invention not only is it possible to easily and quickly fill the boiler 25, but it is also possible to easily and quickly completely empty the boiler of all its liquid content through the discharge opening 38 by the mere act of turning the iron upside down

with the discharge opening unsealed. Accordingly a housewife may readily change from steam ironing to dry ironing without being required to go through involved operations to completely empty the boiler 25.

The iron shown in Figs. 1 and 2 is of the type having a handle structure which is hingedly mounted so it can occupy an operative position as shown in Fig. 1 or a raised inoperative position as shown in Fig. 2, the latter being for the purpose of either filling or emptying the boiler 25.

The handle structure, indicated by the numeral 39, comprises a handle proper 40 carried by front and rear posts 41 and 42, the latter being provided with a rearward extension 43 carrying hinge pins 44 which are received in apertures 45 in the rear portion of the casing 24. As shown in Figs. 1 through 4, the rear of the casing 24 is recessed to receive the rearward extension of the handle and to provide opposite inner walls 46 in which the apertures 45 are disposed.

The front post 41 of the handle structure has a recess 47 providing clearance for the steam dome 31 when the handle structure is in the operative position shown in Fig. 1. Within the recess 47 there is mounted a stopper means for sealing the discharge opening 38 of the steam dome, said stopper means comprising an annulus 48 of yieldable rubber-like material, carried by a disk or plate 49 mounted on a stud 50 passing into a transverse wall 51 in the post 41. The stud 50 has a head 52 engageable with a shouldered bushing 53 to limit downward movement of the stud, and a spring 54 is provided on the stud, engaging the bushing and the disk 49 to yieldably hold the stopper assemblage in a lowered position against the top of the steam dome as viewed in Fig. 1. The annulus 48 is arranged to engage the outer top rim portion of the steam dome 31 so as to seal the discharge opening 38 when the handle structure 39 is in operative position illustrated. Such engagement compresses the spring 54 slightly, enabling the spring to maintain a constant force between the annulus 48 and the steam dome whereby an effective seal is maintained.

In accordance with this invention a simplified stopper means is provided, carried by the handle structure 39, for closing the filler opening 35 when the handle is in operative position. Referring to Figs. 1 and 2, the handle structure 39 includes a base portion 55 which is generally flat and relatively broad, extending between the front and rear posts 41 and 42. On the underside of the base portion 55 a depending boss 56 is provided, having a bore to receive a drive screw 57 carrying a pair of disks 58 and 59 rigidly secured together and having peripheral flanges 60 and 61 respectively between which a sealing annulus 62 is carried. The annulus 62 is formed of rubber or rubber-like material and is adapted to engage the funnel 36 so as to seal the filler opening 35 when the handle structure 39 is in the operative position of Fig. 1.

It will be noted that the stopper assembly is extremely simple and economical to produce, being devoid of demountable connections, and of yieldable means such as springs and the like, since it consists only of four parts, the drive screw 57, the disks 58 and 59, and the annulus 62 as shown in Figs. 1 and 7. Preferably, as illustrated, the disk 58 has an offset central portion which is dished upwardly and apertured to receive the shank of the drive screw 57, the head of said screw being held captive between the dished portion of the disk 58 and the center portion of the disk 59.

In Fig. 11, I show a modified form of stopper for the filler opening. This stopper comprises a sealing annulus 62 carried by flanges 60a and 61a of disks 58a and 59a, said disks being secured together at their center by a stud 57a which is threaded and screwed into a depending boss 56a of a handle structure similar to the structure 39 in Figs. 1 and 2. Between the boss 56a and the disk 58a I provide shims or spacer washers 57b whereby the stop-

per may be adjustably positioned on the handle structure to take care of variations in the dimensions of the component parts of the iron.

I have found, as will hereinafter be brought out, that it is possible to utilize the yieldability of other parts of the iron separate from the stopper assembly in order to enable said assembly to maintain a constant force or pressure on the funnel 36 and an effective seal therewith, and thus the stopper may be simple and economically manufactured as above outlined.

In conjunction with the non-resilient stopper mounting described above, I arrange the stopper assembly for the steam dome 31 to act as a safety valve whereby excess steam pressure in the boiler 25 will unseal the steam dome and allow steam to escape into the recess 47 of the front handle post 41. To accomplish this it is merely necessary to arrange the coil spring 54 to yield under a predetermined desired pressure exerted on it by the disk 49 in response to steam pressure on the underside of the disk. Thus I utilize the resilient mounting of the stopper for the steam dome to enable the stopper for the filler opening to be non-yieldably mounted.

In addition to this, I may utilize the inherent yieldability of the boiler and casing walls, or utilize resilient means associated with the latch mechanism for the handle structure or with the mounting for the funnel 36 either singly or in various combinations, to enable a satisfactory and effective seal to be obtained at the filler opening 35 while still using a stopper having a simplified rigid-type mounting.

Referring to Figs. 1 and 2, it will be noted that the handle structure 39 is hingedly secured to the casing 24 at the rear of the flatiron, at points which are remote from the funnel 36. In conjunction with this I provide a latch mechanism on the base 55 of the handle structure, having cooperable parts on the casing 24 but not on the boiler 25, and since the casing and boiler are secured together at the steam dome which is remote from the filler funnel 36 any force exerted between the funnel and the handle through the stopper for the filler opening would involve the inherent yieldability of the top walls of the casing 24 and boiler 25.

The latching mechanism, Figs. 1 and 2, comprises a knob 63 carried on a shaft 64 passing through the base 55 of the handle structure. At its lower end the shaft 64 has a crosshead 65 adapted to enter a slot 66 in a latching plate 67 secured to the top wall 68 of the casing 24. The shaft 64 carries a washer 64a adjacent the crosshead 65, and further carries a helical compression spring 70 engaging the washer 64a and the underside of the base 55 of the handle structure. Referring to Fig. 2, the knob 63 and latching mechanism are in released position wherein the crosshead 65 may enter the notch 66 if the handle structure 39 should be lowered to operative position. Considering Fig. 1, when the handle structure 39 is in its operative position and the crosshead 65 has passed through the notch 66 and occupies the space below the latching plate 67, the knob 63 may be turned, as through 90 degrees, thereby locking the crosshead below the latch plate 67. During such latching operation slight downward pressure is applied to the handle structure 39, causing the compression spring 70 to compress slightly and forcing the stopper for the filler opening into and against the funnel 36. Such pressure may also cause a slight flexing of the top wall 69 of the boiler 25, all to the end that the crosshead 65 can extend below the latching plate 67 whereupon the crosshead may be rotated for locking purposes. After the handle structure 39 has been latched and downward pressure is removed therefrom, the compression spring 70 will expand to draw up the crosshead 65 against the underside of the latch plate 67. This action will be aided by the force exerted between the stopper 62 and the funnel 36, and will be accompanied by a lessening of the flexure of the top wall

69 of the boiler 25, and a slight flexing of the top wall 68 of the casing 24. Thus I am enabled to use a simplified stopper for the filler opening, having a rigid mounting means, by utilizing the inherent yieldability of the top walls of the boiler and casing.

Referring to Fig. 10, I also provide a novel somewhat yieldable mounting for the funnel of the filler opening. The funnel 36a shown in Fig. 10 is provided with a crimped portion 36b in its side wall, providing partly the effect of a bellows in that the side wall has less rigidity than without the crimp. In Fig. 10 the thickness of the funnel wall has been exaggerated for clarity of illustration. It will be understood, however, that it may be made quite thin, to improve the yieldability. Accordingly, when the handle structure 39 is latched in its operative position the crimped portion 36b of the funnel mounting will enable the funnel to yield slightly. This improved funnel construction may be used in conjunction with the yieldable walls 68 and 69 of the casing 24 and boiler 25, or it may be used by itself, to act independently of yieldability of other parts of the iron.

In Figs. 8 and 9 there is illustrated a modified form of latching means wherein the resilient parts of the latch are so arranged and organized that they can yield under pressure exerted between the handle structure 39 and the body of the iron tending to separate these parts. Therefore the latching mechanism of Figs. 8 and 9 may be used to supplement the yieldable walls of the casing and boiler, and the yieldable mounting for the funnel 36, or the latching mechanism may be used independently of yieldability of said other parts.

As shown, the latch mechanism comprises a knob 71 having a stepped aperture 72 receiving a square portion 73 of a shank 74 carrying at its lower end a crosshead 75. The small portion of the aperture 72 is square to key the knob 71 to the shank 74, and the large portion of the aperture contains a compression spring 76 engaging a head 74a on the top end of the shank 74. Through the shank 74 a cross pin 77 passes, engaging cam surfaces 78 of a depending flange 79 which is preferably integral with the base 55 of the handle structure 39.

Referring to Fig. 9, the latching mechanism is shown in released position. The cross pin 77 is engaging the high parts of the cam surfaces 78, thereby depressing the shank 74 with respect to the base portion 55 of the handle structure and compressing the spring 76 to the fullest extent. This causes the crosshead 75 to project downwardly the greatest amount, enabling the crosshead to pass through the slot 66 in the latch plate 67 and to clear the underside of the latch plate. When the knob 71 is turned, the crosshead 75 will latch under the plate 67 at the beginning of movement, and as the movement progresses the engagement between the cross pin 77 and the cam surface 78 will be relieved or discontinued, enabling the spring 76 to expand thereby forcing the base portion 55 of the handle structure 39 downward. This will result in the stopper for the filler opening being forcibly held against the filler funnel at all times that the handle structure is in the operative position of Fig. 1.

Release of the latch mechanism shown in Figs. 8 and 9 is obviously accomplished by merely turning the knob 77 from the position of Fig. 8 to the position of Fig. 9, through 90 degrees, and thereby again compressing the spring 76 and disposing the crosshead 79 longitudinally of the notch 68 whereby it may be released from the latch plate 67.

It will be noted that by utilizing the resilient parts of the latch mechanism of the handle and the stopper mechanism for the steam dome, and by utilizing the yieldability of the sheet metal walls of the casing and boiler I am enabled to provide a stopper for the filler opening having a simplified rigid type mounting which is less costly. Also, I may obtain this result further by providing the extremely simple yieldable mounting for the

funnel 39a illustrated in Fig. 10, and it will be obvious that various combinations of the above structures may be employed as desired.

In accordance with this invention novel latch means are provided in conjunction with the hinge between the handle structure 39 and the body of the iron whereby the handle structure may be locked in the open position shown in Fig. 2 to provide for easy and quick filling and emptying of the boiler whether the iron is hot or cold. Referring to Figs. 1 through 5, one of the hinge pins 44 is provided with pairs of oppositely projecting locking ears 80 adapted to extend into notches 81 in one of the apertures 45 in the casing 24. The hinge pin 44 having the ears 80 also has a transverse hole 82 receiving a pin 83 which passes through a slot 84 in the rear of the base 55 of the handle structure 39, the outer end of the pin 83 having a knob 85. A compression spring 86 is mounted in back of the hinge pin 44 and normally urges the pin outwardly of its recess, and such movement is limited by the engagement between the transverse pin 83 and the wall of the slot 84.

By this construction the handle structure 39 is automatically latched in the open position shown in Fig. 2 whenever it is swung upward to said position. Upon attaining such position, the hinge pin 44 is shifted axially by the spring 86, causing the locking ears 80 to enter the notches 81. In order to release the hinge latch it is only necessary to grasp the knob 85 and shift it to the right as viewed in Fig. 3, thereby retracting the hinge pin 44 and removing the ears 80 from the notches 81.

Variations and modifications may be made within the scope of the claims and portions of the improvements may be used without others.

I claim:

35. 1. In a steam iron, a boiler having a wall provided with a filler opening, said wall having a rim portion extending around said opening; a stopper; a funnel-like seat for the filler opening, shaped for engagement by said stopper; means comprising crimped walls connecting the seat to the said rim portion of the boiler wall, yieldably mounting said seat on the wall around the filler opening; and means mounting the stopper on the boiler for movement between open position removed from the seat and closed position engaging the seat.
40. 2. In a steam iron, a boiler having a wall provided with a filler opening; a stopper for said opening; means hingedly mounting the stopper on the boiler for movement between positions sealing said opening and removed therefrom; and means carried by the last-named means for latching the stopper in position sealing said opening, said latching means including a latch member and resilient means disposed between the latch member and means mounting the stopper for applying continuous force to move the mounting means in the direction to cause the stopper to maintain the seal thereof.
45. 3. In a steam iron, a sheet metal boiler having a top wall of relatively large area, provided in its central portion with a filler opening; a sheet metal casing overlying the top of the boiler, having an opening aligned with said filler opening; means securing said boiler and casing to each other solely at points remote from said openings; a stopper for said filler opening; means hingedly mounting the stopper on the casing for movement between a sealing position adjacent the filler opening and an unsealing position remote from the filler opening; means on said preceding means and on the top wall of the casing, for latching the stopper in sealing position, said top boiler and casing walls having a degree of yieldability enabling the latching means to flex them in latching the stopper, to provide for continuous sealing force between the stopper and the edge portions of the filler opening.
50. 4. In a steam iron, a boiler having a wall provided with a filler opening; a stopper for said opening; means hingedly mounting the stopper on the boiler for movement between positions sealing said opening and removed therefrom;
55. 5. In a steam iron, a sheet metal boiler having a top wall of relatively large area, provided in its central portion with a filler opening; a sheet metal casing overlying the top of the boiler, having an opening aligned with said filler opening; means securing said boiler and casing to each other solely at points remote from said openings; a stopper for said filler opening; means hingedly mounting the stopper on the casing for movement between a sealing position adjacent the filler opening and an unsealing position remote from the filler opening; means on said preceding means and on the top wall of the casing, for latching the stopper in sealing position, said top boiler and casing walls having a degree of yieldability enabling the latching means to flex them in latching the stopper, to provide for continuous sealing force between the stopper and the edge portions of the filler opening.
60. 6. In a steam iron, a boiler having a wall provided with a filler opening; a stopper for said opening; means hingedly mounting the stopper on the boiler for movement between positions sealing said opening and removed therefrom;
65. 7. In a steam iron, a sheet metal boiler having a top wall of relatively large area, provided in its central portion with a filler opening; a sheet metal casing overlying the top of the boiler, having an opening aligned with said filler opening; means securing said boiler and casing to each other solely at points remote from said openings; a stopper for said filler opening; means hingedly mounting the stopper on the casing for movement between a sealing position adjacent the filler opening and an unsealing position remote from the filler opening; means on said preceding means and on the top wall of the casing, for latching the stopper in sealing position, said top boiler and casing walls having a degree of yieldability enabling the latching means to flex them in latching the stopper, to provide for continuous sealing force between the stopper and the edge portions of the filler opening.
70. 8. In a steam iron, a boiler having a wall provided with a filler opening; a stopper for said opening; means hingedly mounting the stopper on the boiler for movement between positions sealing said opening and removed therefrom;
75. 9. In a steam iron, a sheet metal boiler having a top wall of relatively large area, provided in its central portion with a filler opening; a sheet metal casing overlying the top of the boiler, having an opening aligned with said filler opening; means securing said boiler and casing to each other solely at points remote from said openings; a stopper for said filler opening; means hingedly mounting the stopper on the casing for movement between a sealing position adjacent the filler opening and an unsealing position remote from the filler opening; means on said preceding means and on the top wall of the casing, for latching the stopper in sealing position, said top boiler and casing walls having a degree of yieldability enabling the latching means to flex them in latching the stopper, to provide for continuous sealing force between the stopper and the edge portions of the filler opening.

and means carried by the last-named means for latching the stopper in position sealing said opening, said latching means including a latch member and resilient means disposed between the latch member and means mounting the stopper, for applying continuous force to move the mounting means in the direction to cause the stopper to maintain the seal thereof, said stopper mounting means including a movable handle structure for the iron and said latching means comprising a pin movable axially in said handle structure and protruding therefrom toward the boiler, the said resilient means comprising a spring carried by said pin and normally urging the latter to a less-protruding position on the handle structure.

5. In a steam iron, a boiler having a wall provided with a filler opening; a stopper for said opening; means hingedly mounting the stopper on the boiler for movement between positions sealing said opening and removed therefrom; and means carried by the last-named means for latching the stopper in position sealing said opening, said latching means including a latch member and resilient 10

5
10

means disposed between the latch member and means mounting the stopper, for applying continuous force to move the mounting means in the direction to cause the stopper to maintain the seal thereof, said latching means having a knob for rotating the latch member between the latching and release positions and including cam means cooperating with said latch member and operative in response to rotation of the latch member to released position to retract the resilient means and to remove the continuous force produced thereby.
